United States Patent Office.

ALFRED S. DICKINSON, OF NEW YORK, N. Y.

Letters Patent No. 95,994, dated October 19, 1869.

IMPROVED CURTAIN-FIXTURE DEVICE FOR STOPPING THE MOTION OF CORDS.

The Schedule referred to in these Letters Patent and making part of the same.

To all whom it may concern:

Be it known that I, ALFRED S. DICKINSON, of the city, county, and State of New York, have invented a new and useful Device for Stopping the Motion of Cords and Ropes; and I do hereby declare that the following is a full, clear, and exact description thereof, reference being had to the annexed drawings, making part of this specification, in which—

Figure 1 represents a perspective view of the device, showing its position while the rope which reeyes through it is in motion.

Figure 2 is a similar view, showing the device in the position it assumes in stopping the motion of the rope.

Figure 3 is a front elevation.

The same letters are used in all the figures to designate identical parts.

The nature of my invention consists in producing a device for checking or stopping the motion of cords or ropes in the form of a short tube, through which the cord is passed, and which is pivoted at its upper end, and provided with a slit in one side, said slit being in connection with the orifice at the upper end of the tube, and tapering, in passing down, to near the lower end, where it terminates.

To enable those skilled in the art to make and use my invention, I will proceed to describe its construction and operation.

In the drawings—

A represents the tube or device by which the motion of a cord or rope, B, is to be stopped.

This tube may be constructed, as shown in the drawings, and may be of any desired dimensions. The upper portion of the tube is, in this instance, somewhat enlarged on one side, which enlarged portion is flattened, so as to fit between the flanges of the bridge C, to which it is pivoted by a pin, a, passing through perforations in the flanges and tube. The outer side of the tube—which is opposite the enlargement thereon—is provided with a slit, A', which is of the size of, and connects with the orifice of the tube at top, and thence extends downward, tapering, to near its lower end, at its termination coming to near a point, as shown in fig. 3. The edges of this slit are rounded so as to prevent injury to the cord or rope in wedging into it.

C represents a frame or bridge constructed with out-

wardly-projecting flanges, c, between which the tube A is to be hung, as clearly shown in the drawings. This frame may be secured at any desired point. The particular form of the frame shown, I deem a desirable one where the device is to be used for stopping the motion of the cords of window-curtains; but it is apparent that such frame may be constructed in various forms without deviating from the nature of my invention.

The operation of this device may be described as follows:

I will suppose it to be applied to stop the motion of a cord of a window-curtain. The device having been arranged in the proper place, the lower end of the cord is passed through the tube, from top to bottom, as shown in fig. 1, when it will offer no resistance to the motion of the cord in raising or lowering the curtain. To stop the motion of the cord, throw the tube up to the position shown in fig. 2, when the weight of the curtain will at once wedge the cord into the slit, by the bite of which it will be securely held until the tube is again turned down.

Figure 4 shows a modification of the construction of the tube, which I consider, for many purposes, superior to the one just described. Its distinguishing feature consists in an additional short tapering slit in the lower end of the tube, and opposite the main slit; portion of the periphery of the tube being elongated to have this slit formed in it, as shown, the object being, that the rope, after having been wedged into the outer or upper slit by throwing the tube up, shall form a short break, and then recede into the lower slit, and thus be held more securely.

Having thus described my invention,

What I claim, and desire to secure by Letters Patent, is—

A device for stopping the motion of a cord or rope, consisting of a tube, A, pivoted at its upper end to any suitable frame, and having a tapering slit or slits, A', as set forth.

In testimony whereof, I have signed my name to this specification, in the presence of two subscribing witnesses.

ALFRED S. DICKINSON.

Witnesses:

JAMES WARING,
JESSE OAKLEY.
